SWITCH

John W. Lawson, Anderson, Ind., assignor to
General Motors Corporation, Detroit, Mich., a
corporation of Delaware

Application June 2, 1943, Serial No. 489,389

13 Claims. (Cl. 200—6)

This invention relates to improvements in rotary type switches for use on automotive vehicles and more particularly the military type.

It is an object of the present invention to provide in a switch structure, two separate manual controllers, one of which controls a plurality of circuits and the other to control movements of the circuit controller. This switch is particularly adapted for controlling circuits for four conditions of driving and parking, namely, black-out parking, black-out driving, daylight driving with only the stop light burning when the brakes are applied, and night driving with regular or service head and tail lamps burning.

Another object of the invention is to provide a novel and improved type of switch means having a plurality of "on" positions on each side of an "off" position and having two manually operated members, a pusher member and a rotatable member, so arranged that the pusher member will permit the rotatable member to move the switching means in one direction of rotation to its first "on" position, but prevents further movement of the switching means in said direction to the remaining "on" positions and also to prevent the switching means from moving to an "on" position in the opposite direction of rotation so long as the pusher member is in its normal position. When the pusher member is pushed a certain distance from its normal position the switching means can move by the rotatable member in either direction of rotation to any one of the "on" positions to be selected.

Another object of the present invention is to provide a pair of control members each having means which cooperate with each other so as to prevent accidental turning of the switching means in the wrong direction of rotation and also prevent the switching means from making a complete rotary movement in the other direction of rotation.

Further objects and advantages of the present invention will be apparent from the following description reference being had to the accompanying drawing wherein a preferred embodiment of the present invention is clearly shown.

In the drawing:

Fig. 1 is a longitudinal sectional view of the switch embodying the present invention and taken on the line 1—1 of Fig. 2.

Figs. 2 and 3 are respectively, front and rear views of the switch looking respectively in the directions of arrows 2 and 3 of Fig. 1.

Figs. 4, 5, 6 and 7 are sectional views respectively on lines 4—4, 5—5, 6—6 and 7—7 of Fig. 1.

Referring to the drawing 20 designates a cup-shaped housing or casing having a bottom wall 21 provided with an opening 22 through which a bushing or bearing 23 extends, said bushing has a shoulder at 24 engaging a detent plate 25 engaging the inner side of the wall 21. The bushing 23 and plate 25 are held in a fixed relation with respect to the bottom wall 21 by upsetting the bushing at several places, as at 26, over the outer face of the bottom wall 21 as shown in Fig. 4. The bushing 23 is also provided with a shoulder 27 engaging a washer 28 engaging an instrument panel 29 having an opening through which the bushing extends. The bushing also extends through an apertured index plate 30 and a washer 31. A nut 32 has screw threaded engagement with the threaded end of the bushing 23 which on being screwed thereon clamps the washer 28 between the shoulder 27 of the bearing 23 and the panel 29 and the plate 30 against the panel.

The bearing 23 slidably supports a shaft 35 having a tapered end 36 provided with flats engaging corresponding flats provided by a handle or lever 37. The handle is attached to the shaft 35 by a screw 38. Thus, relative movement between the handle 37 and the shaft 35 is prevented. The other end of the shaft 35 is, preferably, though not necessarily, provided with reduced portions 39 and 40 with the reduced portion 40 journaled in an insulating plate or closure 41. It is to be understood due to the length of the bearing surface of the bushing the portion 40 of the shaft 35 could be eliminated. The shaft in this instance is preferably formed with an integral flange providing radial arm portions 42 and 43 with the arm 42 having a lug or projection 44 extending into a slot 45, see Figs. 1 and 6, in an insulating contact carrier 46. The carrier 46 supports a plurality of contact plates 47, 48 and 49 of triangular formation. The carrier has a central opening through which portions 39 and 40 project loosely so that the carrier is capable of floating free of the portion 40 under the pressure of a single compression spring 50.

The compression spring 50 surrounds the shaft 35 and is interposed between the flange comprising the arm portions 42 and 43 and the contact carrier 46 for the purpose of urging the carrier toward the closure 41 causing the contacts 47, 48 and 49 to engage therewith. Since the contact plates are identical in structure only one will be described in detail. For example, the triangular contact plate 47 may be formed with three spherical bosses or buttons 51, one adjacent each

corner on one side of the plate. On the other side of the plate three shanks 57 are provided which pass loosely through openings 53 provided by the carrier to permit the plate to tilt in infinite directions relative to the carrier. The buttons 51 and the shanks 57 may be made of one piece namely a headed rivet with the shank 57 press fitted into suitable openings in the plate 47. In order to provide a fulcrum or pivot for the plate 47 upon which the plate may tilt to adjust itself for engagement with stationary contacts supported on the closure 41 the central portion of the plate is preferably deformed to provide a boss, thereby providing a fulcrum point 54 for the plate. It will be apparent from Fig. 1 that each contact plate is free to tilt in many directions.

The pressure between the movable contact plates and the stationary contact is substantially equal, because whatever force is imparted from the plate 46 to the contact 47, due to the action of spring 50, is delivered to the point of engagement of the boss 54 when the plate 46 engages the boss. The contact 47 is driven by the carrier 46 due to the fact that the shanks 57 project freely through apertures provided by the carrier. The particular disposition of the contact plates 47, 48 and 49 with respect to the carrier 46 has a three point support provided by the three buttons 51 of the respective contacts 47, 48 and 49. Therefore the pressure exerted by the spring 50 is equally distributed so that each contact button gets one-third and since each contact plate equally distributes its pressure to its individual three contact buttons then it may be said that each movable contact button receives substantially one-ninth of the total pressure exerted by the spring 50. In this way, the movable contact buttons bear uniformly upon the stationary contacts which are flush with the inner surface of the closure 41.

The closure 41 of the switch is made of any suitable non-conducting material, such as fiber or Bakelite which is provided with an ear 55 extending into a notch 56, in the peripheral flange of the cup-shaped housing 20 to locate definitely the position of the closure therewith. The housing has a plurality of tangs 57 bent over the closure 41 by which the closure is attached to the housing 20. The closure 41 supports a plurality of stationary contacts 61, 62, 63, 64, 65 and 66 which are arranged in the same inner circular row with contacts 67 and 68. The contacts 61, 62, 63, 64, 65 and 66 are electrically connected by a strap 70. The base is also provided with an outer row of stationary contacts including contacts 71, 72, 73, 74, 75, 76, 78, 79 and 80. Contacts 73 and 75 are electrically connected by a strap 81. Contacts 67, 78, 79 and 68 are connected together by a strap 82. The straps 70, 81 and 82 are located on the outer face of the closure so that the triangular shaped movable contact plate 47, 48 and 49 shown in Fig. 6 cannot engage the straps.

Referring to Fig. 1 the movable contacts are yieldingly maintained either in the "off" position or any of the four "on" positions by a detent device including the detent plate 25 having five equidistant slots 85 each capable of receiving a ball 86 located in a pocket 87 of arm 42. The ball 86 is urged by a spring 88 toward the plate 25. Since the plate 25 must be located in a definite relation to the case 20 which is located in a definite relation to the closure 41, the plate 25 is provided with an aperture 89, see Fig. 7,

which receives a lug or projection 90 integral with bottom wall 21 of case 20. Rotation of the handle 37 in either direction of rotation is limited by stop means comprising a projection 91 of arm 42 received in an arcuate slot 92 in plate 25, see Fig. 7.

To prevent any inadvertent or accidental movement of the handle 37 in a clockwise direction the "off" position as shown in Fig. 2 the arm portion 43 is provided with a notch 93 intermediate its peripheral edge, to provide abutments 94 and 95 as shown in Fig. 7. The notch 93 receives an enlarged portion or head 96 of a rod or plunger 97 having a cup-shaped push button 98. The enlarged portion 96 will move out of the plane of the arm portion 43 when the button 98 is moved to the left, as viewed in Fig. 1, against the action of a spring 99 retained in a pocket 100 within a hub 101 riveted to the wall 21 of the housing 20 within which the plunger is guided. The spring 99 normally holds the plunger 97 in such position that movement of the handle 37 clockwise from "off" position is limited to one switch closed position. The handle 37 cannot be moved in a clockwise position, as viewed in Fig. 2 or in a counterclockwise position as viewed in Fig. 7. Only when the plunger 97 is manually moved to the left against the action of the spring 99 to shift the enlarged portion 96 beyond the plane of the arm 43 may the handle 37 be moved in either direction of rotation from the "off" position. When the handle moves the arm 43 to its extreme "on" positions and the push button is released the enlarged portion 96 will ride on the unnotched portion of the arm 43. Thus, when the handle returns toward the "off" position and the enlarged portion is between the abutments 94 and 95 the plunger will automatically return to its normal position with a snap action.

The outer face of the bottom wall 21 supports a plate 103 having suitable legends 104 while the handle is provided with a pointer or other suitable indicator 105, adapted to coact with the legends 104 to show the positions occupied by the movable contact members.

The general operation of the switch without taking into consideration the function or position of the plunger 35 will be clear from the foregoing but it may be briefly summarized as follows: When the handle is in the "off" position as shown in Fig. 2 all circuits controlled through the switch are open. However, should the handle 37 be moved in a counterclockwise direction as viewed in Fig. 2 so that the pointer 105 is opposite the legend "Bo-Mk" the movable contacts 47, 48 and 49 will engage stationary contacts as follows: 47 (62-72); 48 (65, 74-75); 49 (77-78). When the handle is moved further in a counterclockwise direction to bring the pointer 105 opposite the legend "Bo-Dr" the movable contacts will engage the following stationary contacts 47 (61, 71-72); 48 (64, 73-74); 49 (67-77). Should the handle be moved in clockwise direction to bring the pointer 105 opposite the legend "Stop-Lt" the movable contacts will engage the following stationary contacts, 47 (63-73); 48 (76); 49 (79-80); and when the pointer is moved further in the clockwise direction to bring the pointer 105 opposite the legend "Hd-Lts" the movable contacts will engage the following stationary contacts; 47 (64, 73-74); 48 (66, 76); and 49 (68, 80).

In the regular operation of the improved construction the movement of the handle 37 from the "off" position to the "stop-Lt" position can take

place without hindrance but the handle cannot be moved to position "Hd-Lts" or the positions "Bo-Mk" and "Bo-Dr" without requiring the manipulation of the plunger 35 because the enlarged portion will be in the path of one or the other abutment 94 or 95. Thus the enlarged portion 96 of the plunger will prevent any inadvertent or accidental movement of the handle to rotate the carrier to bridge stationary contacts to close circuits through the switch. This feature makes it necessary to operate manually the plunger 97 before the handle 37 can be manually operated to close a circuit which would be dangerous if said circuits were closed inadvertently or accidentally.

While the embodiment of the present invention as herein disclosed, constitutes a preferred form, it is to be understood that other forms might be adopted, all coming within the scope of the claims which follow.

What is claimed is as follows:

1. Switch means comprising an axially movable plunger; switch means having its axis paralleling the axis of the plunger and capable of rotating in either direction of rotation from a normal open position to a plurality of closed positions; contacts cooperating therewith; yieldable mechanism for holding the switch means in any one of its positions; and means carried by the plunger cooperating with spaced abutments rotatable with the switch member to permit the switching means to move a certain distance in one direction of rotation to one of the closed positions but preventing the switch means from moving to another closed position in that same direction and preventing the switch means to move in the opposite direction from the normal open position, the displacement of the plunger means from engagement with the abutments permitting the switch means to rotate in either direction of rotation to any one of the closed positions.

2. Switch means comprising, an axially movable plunger; a carrier rotatable in either direction of rotation from a normal "off" position to a plurality of different "on" positions on each side of the "off" position; yieldable contacts supported by the carrier and adapted to bridge stationary contacts in the different "on" positions; cooperating releasable mechanism for holding the carrier in its different positions; a manually operable actuator for rotating the carrier; means movable with the actuator, said means having a slot to receive a head on the plunger, said head permitting rotary movement of the carrier in one direction of rotation to one of the "on" positions upon actuation of the carrier but preventing accidental rotary movement of the carrier in the opposite direction of rotation, said plunger being axially movable so that the head of the plunger is moved beyond the slot of the movable means permitting the actuator to turn the carrier in either direction of rotation with the head riding on the unslotted portion of the movable means; and a spring pressing said plunger in a direction to return the plunger to its normal position when the head is in registry with the notch.

3. In an electric switch the combination of a plunger mounted for straight-line movement and having a manually operated member at one end; a spring for urging the plunger in one direction of its straight line movement; a carrier adapted for rotation in either direction; an actuator for the carrier; an arm carried by the actuator and having a notch for receiving an en-

larged portion provided on the other end of the plunger, said notch being constructed so that the actuator can move the carrier and arm a predetermined distance in one direction of rotation relative to the plunger to permit the carrier to shift yieldable contacts.

4. An electric switch comprising in combination; an axially movable plunger; a rotatable contact carrier having an "off" position and a plurality of "on" positions on each side of the "off" position; floating contacts carried by the carrier and adapted to bridge stationary contacts; an actuator for rotating the carrier; an arm movable with the actuator and having a

slot to receive a head on the plunger to permit rotary movement of the carrier in one direction of rotation to one of the "on" positions upon operation of the actuator but preventing accidental rotating movement of the actuator in the opposite direction of rotation, said plunger being axially movable so that its head is moved out of the plane of the arm permitting the actuator to turn the carrier in either direction of rotation with the head riding on the unslotted portion of the arm to hold the plunger in its depressed position; and resilient means urging the plunger in a direction to return the plunger to its normal position when the head is in registry with the slot.

5. Switch means comprising, an axially displaceable plunger provided with a head; a rotatable shaft; a contact carrier driven by the shaft; contact elements supported by the carrier and adapted to bridge stationary contacts; means movable with the shaft having a pair of abutments; a head carried by the plunger and adapted to extend into the space between the abutments so that the head will permit the shaft to rotate in one direction of rotation to move the movable means and the carrier to bridge certain contacts but preventing accidental movement of the shaft in the opposite direction, said plunger being capable of axial movement with respect to movable means so that the head is moved out of the plane of the movable means permitting the shaft to turn in either direction of rotation.

6. A switch device providing a bearing; member guided for sliding movement in the bearing to either of two positions; resilient means for normally holding the member in one of said two positions; a rotatable shaft; a circuit closer driven by the shaft; a plate having a pair of abutments and rotatable with the shaft, said abutments adapted to engage a head provided by slidale member, said abutments being spaced to permit a predetermined rotation of the shaft in one direction of rotation but preventing accidental rotation of the shaft in the opposite direction, movement of said sliding member against the action of the resilient means to move the head out of the path of the abutments permits the shaft to rotate in either direction of rotation with the head riding on the plate, said resilient means returning the sliding member to its normal position when the head is between the abutments.

7. In a switch, the combination with a plunger having a head mounted for axial movement; of a spring for urging the plunger in one direction; a rotatable actuator; a floating contact carrier driven by the actuator; a plate attached to the actuator; resilient means about the shaft and resting on the plate and bearing against the carrier; movable contacts carried by the carrier; a support providing stationary contacts with which

the movable contacts cooperate; abutments provided by the plate and coacting with the head of the plunger to permit a predetermined movement of the actuator in one direction of rotation but preventing accidental movement of the actuator in the opposite direction, axial movement of the plunger so that the head is moved beyond the abutments permitting the actuator to move in either direction of rotation; and cooperable releasable mechanism for holding the actuator in its different positions.

8. In a switch, the combination with a plunger having an enlarged portion mounted for sliding movement; of a spring for urging the plunger in one direction; a rotatable actuator; a floating contact carrier; radial extensions mounted on the shaft, one of said extensions having means for driving the carrier while another extension is provided with a notch to receive the enlarged portion of the plunger, said head cooperating with the notch to control the rotatable movements of the actuator, said notch being greater in cross dimension than the head and so positioned in relation thereto to permit a predetermined movement of the actuator in one direction of rotation but preventing accidental movement of the actuator in the opposite direction, axial movement of the plunger permitting the head to move from the confines of the notch allowing the actuator to move in either direction of rotation; and resilient means for urging the movable contacts and the actuator axially in opposite directions.

9. In a switch, the combination comprising; an axially movable plunger and a rotary member having their axis in parallelism and mounted for independent manual operation; a plurality of yieldable contacts actuated by the rotary member; stationary contacts arcuately disposed about the axis of the rotary member and adapted to be engaged by the yieldable contacts; stop means carried by the axially movable member limiting the angular motion of the rotary member in the normal position of the plunger to a certain arc in one direction of rotation and preventing accidental motion of same in the opposite direction, the axial displacement of the stop means by the plunger permitting the rotary member to move in a greater arc in either direction of rotation; and additional stop means limiting the motion of the rotary member in either direction of rotation.

10. In a switch, the combination comprising, a slideable member and a rotary member having their axes in parallelism and mounted for independent manual operation; a carrier carrying yieldable contacts driven by the rotary member; stationary contacts adapted to be engaged by the movable contacts; and means carried by the slideable member located in the path of means movable with the rotary member to limit the angular motion of the rotary member in one direction of rotation but preventing angular motion of the rotary member in the opposite direction when

the slideable means is in its normal position, the removal of the slideable means from its normal position and out of the path of the rotatable means permitting the rotary member to increase the angular motion of the rotary member in said one direction of rotation and also permitting the rotary member in the opposite direction of rotation from its normal position.

11. In a switch of the kind specified having a shaft adapted for rotation in either direction from a normal position and provided with a lateral flange having a peripheral notch to provide spaced shoulders; a plunger mounted relative to the shaft and having a head normally biased into the same plane of the flange and disposed in the space between the shoulders so that one shoulder is adjacent the head to prevent angular motion of the shaft in one direction but having the other shoulder positioned to permit angular motion in the opposite direction until the other shoulder engages head, said plunger being movable in a direction which is transverse to the plane of the flange to move the head out of the plane of the flange and thereby permit greater angular motion of the shaft in said opposite direction and also permit angular motion of the shaft in said one direction from its normal position; and means for limiting the angular motion of the shaft in both directions.
12. A switch of the kind specified having a rotatable shaft provided with a lateral flange; a plunger mounted for axial movement relative to the flange; abutments on the flange between which the one end of the plunger normally rests, said plunger being biased in one direction so that said end normally cooperates with the abutments to limit the angular motion of the shaft in one direction and preventing angular motion thereof in the opposite direction, said plunger being capable of axial movement so that the end will be out of the path of the abutments to permit selectively angular motion of the shaft in either direction of rotation.

13. A controller comprising in combination, a rotatable manually operable plate having a depression spaced from its axis of rotation; a spring pressed rod having its axis paralleling the axis of the plate and having one end thereof projecting into the depression, said end normally engaging one end of the depression to prevent the plate from rotating in one direction but permitting the plate to rotate in the opposite direction until the specified one end of the rod engages the other end of the depression, said rod being disposed for manual operation to move the specified end of the rod out of the depression whereby the plate can rotate in greater arcs in either direction, said specified end of the rod engaging the plate upon manual release of the rod and same is out of registry with the depression, said rod reentering the depression when same is in a position to receive the rod.

JOHN W. LAWSON.
